UNITED STATES PATENT OFFICE.

JAMES H. OTTO, OF BEELER, AND EDWARD C. YOUNG, OF WALLACE, IDAHO.

TOBACCO-CUTTER.

1,316,056.

Specification of Letters Patent. Patented Sept. 16, 1919.

Application filed March 24, 1919. Serial No. 284,831.

To all whom it may concern:

Be it known that we, JAMES H. OTTO and EDWARD C. YOUNG, citizens of the United States, residing at Beeler and Wallace, respectively, in the county of Shoshone and State of Idaho, have invented certain new and useful Improvements in Tobacco-Cutters, of which the following is a specification, reference being had to the accompanying drawings.

This invention relates to an improved tobacco cutter, and an object of the invention is to provide an improved device of this kind, which is very simple and efficient in construction, exceedingly useful in practice, and owing to its simplicity may be manufactured for a small cost and sold at a reasonable profit.

The invention further aims to provide a tobacco cutter including a base having a chamber for water or the like, upstanding opposite guides, a severing member mounted in the guides including actuating means therefor, whereby as the severing member is lowered, in the act of cutting a piece of plug tobacco or the like, the severing element partially enters the chamber, in order to be damped by the water therein.

The invention further aims to provide wipers consisting of rubber or a composition of rubber and canvas upon opposite sides of an opening through which the severing element passes, for wiping the opposite faces of the severing element, when its cutting edge portion and the opposite faces adjoining thereto are withdrawn from the chamber, for wiping the opposite faces of the severing element and removing the gummy substance thereon.

The invention further aims to provide means for holding or clamping these opposite wiping jaws to the upper portion of the wall of the chamber formed in the base, said means being of such construction as to permit it to be removed for repairing or renewing the wiping jaws.

The invention further aims to provide a filling opening, through which the water may be poured into the chamber. It is obvious that if desired one of the wiping jaws may be removed whereby the water may be poured into the chamber.

While the design and construction at present illustrated and set forth is deemed preferable, it is obvious that as a result of a reduction of the invention to a more prac-

tical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view partly in elevation and partly in section, showing the tobacco cutter constructed in accordance with the invention, and illustrating the cutting knife or severing member on the verge of passing between the wiping jaws in full lines, showing the angle of the cutting edge whereby a shearing action may be attained and illustrating the knife raised in dotted lines, further illustrating the fact that there is a tilt to the knife in its movement.

Fig. 2 is a sectional view on line 2—2 of Fig. 1.

Fig. 3 is a horizontal sectional view on line 3—3 of Fig. 1.

Referring more especially to the drawings 1 designates a base, which may be constructed of any suitable material, preferably metal or the like, which may be galvanized or oxidized or otherwise finished, so as to present a finished appearance. This base is provided with suitable apertures or openings 2 for the reception of fastening means, whereby the cutter may be mounted upon the counter in the cigar store or other place. Rising upwardly from the base and integral with the base is an enlargement 3, which is hollowed out to provide a chamber 4, for the reception of water, for the purpose to be herein-after set forth.

Rising upwardly from the upper surface of the enlargement, that is on the surfaces of the end walls of the chamber, and constructed integral therewith are standards 5, the adjacent edges of which have guide channels 6, in which a severing element or knife 7 is guided. This knife has an upwardly protruding extension 8.

Secured to the opposite sides of the standards 5 and in parallelism thereto are side plates 9, which are spaced, the space 10 thereof forming a guide for a lever 11, which is pivotally mounted at 12 between the plates. This lever 11 is provided with a bifurcated lug 13, in the bifurcation of which the extension 8 is pivotally con-

nected, whereby as the lever is raised and lowered on its pivot, the severing element may be actuated or raised and lowered in its guide channels.

5 Wiping jaws 14 are mounted upon the upper surfaces of the longitudinal walls of the chamber. These wiping jaws may in the present instance be constructed of rubber or a composition of rubber and canvas, 10 particularly the canvas and rubber. The adjacent edge portions of the wiping jaws are positioned between the standards 5, so that the notches 15 may engage the standards. However, these edge portions are 15 spaced to provide the wiping jaws proper 16, and owing to these jaws being spaced a slot 17 is provided, through which the severing element or knife passes on its downward movement. By means of sheet 20 metal plates 18, provided with apertures 19 for the reception of fastening screws or the like, the wiping jaws are secured to the walls of the chamber. These plates are detachably fastened in position, so that one 25 or the other may be removed to permit of repairs, and also for cleaning the chamber, which becomes more or less gummy. Carried by one of the standards in any suitable manner is a filling funnel 20, the 30 lower end of which has a passage of communication 21 with the chamber, so that water may be allowed to enter the chamber. It is obvious that in order to fasten one of the members (constituting one of the 35 wiping jaws) to the wall of the chamber, the wiping jaw and the plate for securing it in place are provided with cutaway portions, to engage about the lower end of the filling funnel.

40 It is to be observed that the severing element or knife is loosely mounted in its guide channels, so that when the severing element or knife is on its downward stroke, it becomes tilted angularly in its guides, so as to 45 cause the lower severing edge of the knife to assume an acute angle to the securing plates, as the lower cutting edge approaches the plug of tobacco, so as to insure a shearing action on the plug, thereby more efficiently cutting the tobacco, without leaving a rough edge, or without tearing the plug, or mashing the same adjacent the cut. Owing to the lever 11 being pivoted at 12, to one side of the center of the frame of the 50 cutter, as shown in Fig. 1, and since the pivotal connection between the lug (which projects at right angles to the lever 11 and downwardly) and the upwardly protruding extension 8, moves in an arcuate path whose 55 center is the pivot 12, and by virtue of the loose mounting of the knife, the knife assumes a tilting action within its guides, during its vertical movements. For instance, when the lever 11 is swung upwardly, 60 the pivotal connection between the ex-

tension 8 and the lug 13 will move from the vertical center of the frame, that is laterally to one side of the vertical center of the frame, causing the knife to tilt in its guides, and this tilting action is capable of being performed, owing to the loose mounting of the knife in the guides. When the knife tilts in this manner, particularly on its downward stroke the cutting edge has a shearing action on the plug of tobacco, 70 thereby more efficiently cutting the tobacco without leaving a rough edge, or without tearing the plug, or mashing the same adjacent the cut. 75

The invention having been set forth, what is claimed as new and useful is.

1. In a tobacco cutter, the combination with a base provided with a chambered enlargement, the chamber of which being adapted to receive water or the like, guides 85 rising upwardly from the end walls of the chamber, members secured to the upper faces of the longitudinal walls of the chamber and having spaced wiping jaws, thereby providing a slot for the reception of a severing member, a severing member loosely mounted in the guides, the sharpened portion thereof adapted to enter the slot, whereby the opposite faces of the member may be wiped by the wiping jaws, side plates 90 secured to and spaced by the upright guides, and a lever pivoted between the side plates, said lever having means extending at right angles to the lever and having a pivotal connection with the member, said pivotal connection adapted to swing in an arcuate path concentric with the pivot of the lever, whereby, as the lever is moved to lower the member, the member will be tilted, during its 95 shearing action on the plug. 100

2. In a tobacco cutter, the combination with a base provided with a chambered enlargement, of guides rising upwardly from the end walls of the chambered enlargement, a tobacco cutting knife loosely mounted in 110 the guides, members secured to the upper faces of the longitudinal side walls of the chamber and having their adjacent edge portions spaced to provide a slot, said edge portions constituting wiping jaws, engageable 115 with the opposite faces of the knife, which passes through the slot on its downward stroke, for wiping the opposite faces thereof, opposed spaced plates secured to the upper parts of the guides, a lever pivotally mounted between the plates, a connection between the lever and the knife, said connection being movable in an arcuate path concentric with the pivot of the lever, whereby it may move laterally from the vertical center of 120 the plates, so as to tilt the knife loosely in the guides, as it is lowered, thereby causing the cutting edge of the knife to assume an acute angle to the wiping jaws, during its 125 shearing action on the tobacco. 130

3. In a tobacco cutter, the combination with a chambered body having upstanding grooved guides, plates secured to the upper face of the chambered body and having 5 members extending between the guides and spaced to form a slot, members secured between said plates and the body and having their adjacent edges protruded beyond the adjacent parts of the plates, thereby constituting 10 wiping jaws, between which a cutting knife may pass, a knife blade loosely mounted in the guide, a lever pivotally mounted to one side of the center of the plates, a pivotal connection between the lever and the 15 knife, adapted to move away from the vertical center of the plates in an arcuate path concentric with the pivot of the lever, thereby causing the knife to tilt in its guides, causing the cutting edge of the knife to assume 20 an acute angle to the wiping jaws, during the shearing action of the cutting edge.
4. In a tobacco cutter, the combination with a body having a water receiving chamber, said chamber having a water entrance 25

funnel, of upright parallel guides on the body, a knife loosely mounted in the guides, spaced wiping jaws forming a slot through which the cutting edge of the knife passes, means for securing the jaws to the body, 30 spaced elements on the guides, a lever having a pivotal connection between the elements, to one side of the vertical center of the elements, said lever having a lug extending laterally and a pivotal connection 35 between the knife and the lug adapted to move laterally from the vertical center of the elements and in an arcuate path concentric with the pivot of the lever, thereby tilting the knife, so that its lower edge will assume 40 an acute angle to the wiping jaws during the shearing action on the tobacco.

In testimony whereof we hereunto affix our signatures in the presence of two witnesses.
